(57) **CLAIM**

The ornamental design for a mobile phone, as shown and described.

DESCRIPTION

FIG. 1 is a rear perspective view of the mobile phone;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof; and,
FIG. 8 is an enlarged rear view for clarity of illustration. The broken lines depict portions of the mobile phone that form no part of the claimed design. The unshaded region in FIGS. 1, 3 and 8 between the claimed solid line edges and the broken line forms no part of the claimed design. The dash-dot broken line rectangle in the FIG. 8 view is used to identify the enlarged view, is for reference purposes only, and forms no part of the claimed design.
